Thomastachie

UNITED STATES PATENT OFFICE.

OSIAS M. GOTTESMAN, OF NEW YORK, N. Y.

CLOSURE.

Application filed December 16, 1921. Serial No. 522,818.

To all whom it may concern:

Be it known that I, OSIAS M. GOTTESMAN, a citizen of the United States, residing at New York city, in the county of New York 5 and State of New York, have invented certain new and useful Improvements in Closures, of which the following is a specification, reference being had therein to the accompanying drawing.

10 My invention relates to closures for receptacles and more particularly has reference to and is illustrated in the accompanying drawings in its application to a water bottle as a stopper therefor.

15 Fig. 1 illustrates in longitudinal section, parts being broken away, the upper part of a water bottle with my closure in position. Fig. 2 is a cross-section of the valve portion of said closure or stopper. Fig. 3 is a longi-

20 tudinal view partly in section illustrating a modified form of stopper embodying the same principles of construction. Fig. 4 is a plan view looking right to left at Fig. 2 and upon which Fig. 2 is a cross-section on

25 the line 2—2 thereof. Fig. 5 is a view looking from left to right at Fig. 2. Fig. 6 is a longitudinal section of the wall or cylinder of the closure. Fig. 7 is a similar view illustrating a modification. Fig. 8 is an end 30 view looking at the cylinder or wall of the closure shown in Figs. 6 and 7.

9 indicates the neck of the water bottle within which the cylinder or wall 10 of the closure or stopper is suitably retained in the 35 usual well known manner. 11 indicates the key or handle of the valve which projects upwardly into the flared neck 12 of the bottle as shown. This key is preferably stamped out of sheet metal such as brass

40 which is of course preferably nickel-plated and is provided with a series of lateral projections such as 13 which engage the thread or spiral grooves 14 of the cylinder 10 shown to better advantage in Fig. 6, the top lateral 45 projections 15 serving as a stop to prevent the key 11 from passing into the bottle through the neck thereof.

At the base of the key is provided another projection 16 for engaging the valve 17 and 50 said valve is provided with a seating or central recess 18 for said projection 16 which after being introduced therein is retained by the lugs or flange 19 which is turned over as shown in Figs. 1 and 3, thereby rotatably securing the projection 16. This 55 valve 17 is also provided with circumfer-

ential flanges 20—21 between which rubber or other suitable sealing ring such as 22 may be retained as shown in Figs. 1 and 3, and which engages the lower rim of the wall or cylinder 10 thereby closing the same and preventing the passage of the water or other liquid through the neck of the bottle, from which it will be observed that as the key is turned in one direction the valve 17 is unseated by being depressed downwardly thereby allowing the contents of the bottle or contents to be supplied thereto, to pass freely through the neck of the bottle and also through the opening 23 in the key 11. 60 When the key 11 is turned in the reverse direction the valve 17 rises compressing the sealing ring 22 between the cylinder 10 and valve 17 thereby hermetically sealing the 65 neck of the bottle. 70 75

In the modification shown in Fig. 3, the handle 11' of the key it will be observed is elongated sufficiently to pass through the cylinder of the valve, and it will also be observed that the shoulder projections 15' 80 project upwardly. The key is stamped in this form and is attached to the valve 17 when it is desired to introduce it through the neck of the bottle from the inside thereof, in which case the cylinder portion of 85 the valve shown in Figs. 6 and 7 may first be secured in the neck of the bottle, after which the key and valve being introduced therethrough by passing through a hole in the side of the bottle which is subsequently 90 sealed, is screwed home and the shoulders 15' are then thrown down as indicated in dotted outline at 15'' in Fig. 3, thereby preventing the valve from rotating back into the bottle. 95

The cylinder portion of the valve shown in Fig. 7 instead of being cut out of the metallic cylinder as shown in Fig. 6, may be stamped or pressed from sheet metal or other suitable material forming corrugated or crinkled walls as shown, and in fact various modifications may be made in the construction and arrangement of parts without departing from the spirit of the invention as claimed. 100

I claim:

1. In a closure of the class described, a valve and cylinder wall therefor, one end of said wall forming a seating for said valve, a key for opening and closing said valve 110 and means in combination with said key and said wall for moving said valve axially

thereof, a passage through said key for the flow of liquid through said valve.

2. In a closure of the class described, a valve and cylinder wall therefor, one end of said wall forming a seating for said valve, a key for opening and closing said valve and means in combination with said key and said wall for moving said valve axially hereof, said key interlockingly rotatable upon 10 said valve.

3. In a closure of the class described, a valve and cylinder wall therefor, one end of said wall forming a seating for said valve, a key for opening and closing said valve and 15 means in combination with said key and

said wall for moving said valve axially thereof, said key spirally engaged in said wall.

4. In a closure of the class described, a valve and cylinder wall therefor, a key for operating said valve with relation to said wall, said key stamped out of sheet metal, and means independently of the handle of said key for preventing the same from passing through said wall, said key being 20 adapted to be passed through the wall of said valve before assembling.

In testimony whereof I hereunto affix my signature.

OSIAS M. GOTTESMAN.
